UNITED STATES PATENT OFFICE.

ROBERT M. ROBINSON, OF COLUMBIA, MISSOURI, AND HARRY M. McDONALD, OF HARTFORD, CONNECTICUT, ASSIGNORS TO THE COLUMBUS DENTAL MANUFACTURING COMPANY, A CORPORATION OF OHIO.

DISPLAY HOLDER.

1,404,164.

Specification of Letters Patent. Patented Jan. 17, 1922.

Application filed August 25, 1920. Serial No. 405,916.

To all whom it may concern:

Be it known that we, ROBERT M. ROBINSON and HARRY M. McDONALD, citizens of the United States, residing at Columbia, 5 county of Boone, State of Missouri, and Hartford, county of Hartford, and State of Connecticut, respectively, have invented certain new and useful Improvements in Display Holders, of which the following is a 10 specification.

This invention relates to an improved display holder for use in conjunction with artificial teeth, and has for its primary object to provide a structure in the form of 15 a holder which is of such nature that artificial teeth may be quickly and positively connected therewith for purposes of display and yet may be readily disconnected from said holder whenever desired, the construction being such as to permit of the handling 20 of the mounting upon which the artificial teeth are carried and to enable such mounting to be subjected to the jolts and stresses incident to handling operations, without permitting the teeth to become accidentally disconnected from their positions of application 25 upon the holder or mounting.

For a further understanding of the invention, reference is to be had to the following description and to the accompanying drawing, in which:

Figure 1 is a front elevation of the improved mounting for artificial teeth, which forms the subject of the present invention,

Figure 2 is a transverse vertical sectional view taken along the plane disclosed by the line 2-2 of figure 1, and

Figure 3 is a horizontal sectional view taken along the plane indicated by the line 40 3-3 of figure 2.

In the accompanying drawing the improved mounting or holder comprising the present invention has been indicated by the numeral 1. This member is adapted to be 45 used for the purpose of displaying artificial teeth and to provide means whereby such teeth upwardly so that their slots will retained in their positions of application upon the mounting. In way of introduction it 50 may be stated that dealers have experienced some difficulty and annoyance in handling artificial teeth for the reason that when such teeth are placed into or removed from retaining cases or receptacles the mountings

therefor are naturally subjected to a certain 55 amount of shock and jar, which in the past has frequently resulted in a considerable number of the teeth becoming loosened or disconnected from their positions upon the mounting, thereby necessitating a tedious replacement of the teeth as well as supplementing the teeth which inevitably become lost by such accidental removals. However, it is believed that by the use of the mounting comprising the present invention these 60 other analogous objections on the part of those handling artificial teeth will be eliminated, and a device provided whereby the teeth may be securely mounted in a manner that will be free from the objections of dis- 65 placement and loss.

To illustrate the invention the mounting 1 is shown as being employed for the purpose of supporting a plurality of artificial teeth 2, in order that the latter may be handled 70 and displayed in the aforesaid manner. These teeth, it must be observed, may be of any desired formation, construction, or manufacture and it should be particularly noted, therefore, that the same need not be of the 75 make and design disclosed in the drawing and hereinafter more or less specifically referred to and described, but that the invention is adapted to be used in conjunction with many other varying types of artificial 80 teeth, and it is intended that the scope of the invention shall be so construed. The teeth 2 are each formed to comprise a body portion 3, which embraces a curved front 85 4 and may be made of porcelain or any other 90 suitable material, the rear face 5 of the body portion is provided with a vertically disposed slot 6, whose lower end terminates an appreciable distance above the cutting edge 95 7 of the tooth and thereby defines a smooth 100 unbroken portion 8 therebetween. The slot 7 is so formed as to embody a relatively enlarged inner portion 9 and a restricted lateral outlet 10 which opens to the rear face 5 of the tooth 2. The mounting 1 consists 105 of a base or backing 11 of any suitable size or formation, the same in this instance embodying a row of spaced holding members 12. Each of the latter is formed to comprise a pointed shank portion 13, which is suitably driven into the backing 11 so as to be embedded in the latter and to be thus rigidly positioned, the shank portion terminating

outwardly in a relatively enlarged cylindrical head 14. This head is adapted to be received within the inner portion 9 of the slot 6, while the contiguous portion of the shank 13 is positioned within the reduced outlet 10 of said slot. By this construction it will be manifest that the teeth 2 may be connected with the members 12 by positioning the open upper ends of the slot 6 immediately beneath the outer projecting ends of the holding members. Then, by moving the teeth upwardly, the outer ends of said holding members will be positioned within the slot 6 so that the teeth will be fastened to the backing 11 and prevented from separating outwardly or laterally from the latter.

Prior constructions have usually relied upon the friction between the heads 14 of the holding members and the interior walls 20 of the slot 6 to retain the teeth 2 in their applied positions upon the mounting, but practice has disclosed that when this construction alone is employed, the teeth are very apt to slip or become accidentally disconnected from their positions of engagement with the holding members 12, and, as above stated, when this happens the teeth are liable to become lost or, at least, a considerable amount of tedious labor is involved 30 in effecting their replacement. To overcome this, the present invention contemplates providing a longitudinal groove 15 within the backing 11 at a position beneath the members 12, said groove being so disposed as to 35 extend in parallelism with said holding members. In this groove there is seated a strip 16 of rubber or some other equivalent material, and it will be observed, upon reference to figure 2, that the strip 16 is of 40 such cross sectional area that its outer face 17 will extend an appreciable distance beyond the companion face 18 of the backing 11. By virtue of this construction it will be manifest that when the teeth 2 are 45 connected with the holding members, it will be necessary to compress local portions of the strip 16 in order that the upper ends of the slots 6 may be positioned to register with the enlarged heads of the holding members 12. Then, when the teeth are connected with the holding members by forcing the teeth upwardly so that their slots will receive the holding members in the manner disclosed in Figure 2, it will be evident that 55 the compressed state of the strip 16 will be retained, so that said strip may exercise its resilient force in maintaining sufficient friction between the holding members and the teeth to prevent accidental disengagement of the latter from their positions of 60 application upon the backing 11.

In view of the foregoing it will be apparent that the present invention provides simple, practical and efficient means for permitting of the display of artificial teeth in connection with their holders or mountings, and that the arrangement is such that, while the teeth may be readily detached yet their connection will be such that the same will be prevented from becoming accidentally disengaged from connection with the holding members. While the foregoing description specifically sets forth what is now believed to be the best mode of applying the principles of the invention, yet it should be understood that the description does not necessarily measure the invention, except as the latter is defined by the following claims.

What is claimed is:

1. A display mounting for artificial teeth, comprising a base of suitable form, a holding member rigidly carried by said base and having a projecting end, said end being arranged for detachable connection with an artificial tooth, and a resilient element carried by said base serving to engage an artificial tooth when carried by said member and to exercise sufficient pressure thereon to retain the top in secured engagement with said member.

2. A display mounting for artificial teeth, comprising a base of suitable form, a holding member having an enlarged projecting portion carried by said base, the projecting portion of said member being arranged for slidable connection with the rear face of an artificial tooth, and a rubber insert designed for engagement with the rear face of said tooth, whereby the latter will be maintained in secured engagement with said holding member.

3. In a carrier for artificial teeth, a base, a metal clip embedded in said base, said clip being provided with an enlarged head arranged to project beyond the tooth receiving surface of said base, said head being positioned so as to be slidably received within a slot formed in the rear face of an artificial tooth, and a rubber insert embedded in said base and having a portion arranged to project beyond the tooth receiving surface of said base, whereby said insert will be positioned to engage the rear face of a tooth received by said clip and to prevent accidental disengagement of a tooth from engagement with said clip.

In testimony whereof we affix our signatures.

ROBERT M. ROBINSON.
HARRY M. McDONALD.
